VEHICLE TILTING MACHINE

Ernst C. Claus, Chicago, Ill., assignor to Moto-Sway Corporation of America, Chicago, Ill., a corporation of Illinois

Application December 30, 1935, Serial No. 56,657

13 Claims. (Cl. 60—97)

This invention relates to vehicle tilting machines, and more especially to machines adapted to facilitate and improve the oiling and greasing of automobiles and other vehicles by alternately raising and lowering the body of the vehicle relatively to its springs, so that oil or grease injected into the spring joints or knuckles of the springs and between the leaves of the latter is more effectively distributed. Rocking automobile jacks of this general type are broadly known and quite extensively used in public garages and filling stations, and among the objects of the invention are: to provide a machine of the fluid pressure operated type that, instead of elevating one side 5 of the vehicle and simultaneously lowering the other, as is the common practice, will elevate and lower one side, and then elevate and lower the other, and so forth, since this manner of operation better and more fully opens up the joints for penetration by the lubricant than the known method wherein one side of the vehicle is rising while the other is descending and vice-versa; to provide a device permitting one jack only to be operated if lubrication is required on one side 10 only; to provide an improved device of the character indicated that is wholly automatic and in which the timing and length of each stroke may be very easily varied to suit conditions; and, generally, to provide an improved vehicle rocking jack for lubrication purposes.

Still other objects and attendant advantages of the invention will be apparent to persons familiar with the art from the following detailed description, taken in connection with the accompanying drawings, in which I have illustrated one practical and approved embodiment of the principle of the invention, and wherein—

Fig. 1 is a side elevation of the device, broken out between its upper and lower ends, and partly in vertical section.

Fig. 2 is a side elevation, partly in vertical section, of the motor of the left hand jack of Fig. 1, as viewed on the line 2—2 of Fig. 1.

Fig. 3 is a vertical section on the line 3—3 of Figs. 4 and 5.

Fig. 4 is a fragmentary view partly in elevation and partly in vertical section on the offset line 4—4 of Fig. 5.

Fig. 5 is a top plan view, in cross-section through the plunger stem on the line 5—5 of Fig. 1.

Fig. 6 is a horizontal section on the line 6—6 of Fig. 1.

Fig. 7 is a vertical section on the line 7—7 of

Fig. 2, with the cylinder and plunger partly broken out and in section.

Fig. 8 is a diagrammatic view of the two motors, showing the parts thereof spaced apart, with arrows showing the course of the air, the solid line arrows indicating the pressure air and the dotted line arrows indicating the exhaust air.

Fig. 9 is a vertical section of a self-closing valve which, admits pressure fluid to the motor of the master valve.

Fig. 10 is a perspective detail of a striker that opens the self-closing valve.

As shown in Fig. 1, the device employs two fluid pressure jacks designated as a whole by A and B respectively, the motors of which, when both jacks 15 are used, are connected by lines of hose. The parts of these two jacks are for the most part identical, and, for brevity and convenience of description, I will first describe the jack A appearing at the left of Fig. 1, and the parts of jack B which 20 are duplicates of parts of jack A will be identified by the same reference numerals with a prime (') exponent.

The device may be mounted either in a pit, or beneath an overhead runway, in such a position 25 that the saddles on the top ends of the jacks may liftingly engage with the side frame members of the automobile chassis frame, as usual in jacks of this type, and as indicated in Fig. 1.

Describing then the jack A, 10 designates the cylinder shell of its motor, the upper and lower ends of which are closed by plates or heads 11 and 12, these plates or heads being rigidly spaced by opposed rods 13 and connected by tie-rods 14. 35 Within the cylinder 10 is a hollow plunger 15 formed with a suitably packed head 16 (Fig. 7) at its lower end. Locked to the upper end of plunger 15 as by a set-screw 17 (Fig. 4) is the lower section 18 of a tubular plunger stem, the 40 upper section 19 of which telescopes within the lower section, and is formed with spaced transverse holes 20. Keyed to the upper end of the lower section 18 is a collar 21, and swiveled on the collar 21 is a hand wheel 22 having a transversely apertured hub adapted to receive a cross-pin 23 engaged with any of the holes 20 to thereby vary the effective length of the plunger stem. In a tapped cap 24 on the upper end of the stem section 19 is entered the threaded shank 25 of a 50 saddle 26 adapted to engage with the channel side frame members (shown in dotted lines in Fig. 1) of the chassis frame of the car. A rough adjustment as to height is first made by the pin 23, and then a fine adjustment is effected by the threaded 55

shank 25 of the saddle to initially bring the latter into contact with the side frame member. To render the jack readily shiftable to the required position beneath the car, the bottom plates 12 of the motors are extended to provide axle bearings for trundle wheels 27 that may be cushioned by springs 28 (Fig. 7).

Describing now the valves, ducts, controlling members and other details of the jack motor, set 5 cured to or integral with one end of the base plate 12 is a casting 29 formed with an air supply duct 30 (Figs. 3 and 8) leading into the bottom of cylinder 10, and with an exhaust duct 31 that communicates with a short exhaust pipe 15 10 32 containing a throttle valve 33 by which the speed of descent of the plunger 15 may be regulated. To one end of the casting 29 is attached a disc 34 formed with supply and exhaust ports 35 and 36 (Fig. 8). The port 35 communicates 15 20 with a groove 37 on the reverse side of the disc 34, and the port 36 communicates with a groove 38 on the reverse side of the disc 34, and both of the grooves 37 and 38 are in continuous register with the ducts 30 and 31 respectively. Extending through the block 29 and disc 34 is a 25 30 rockshaft 39, fast on the inner end of which is a reversing valve in the form of a segment plate 40, having on its rear side an arcuate groove 41 through which the supply port 35 is alternately thrown into and out of communication with the exhaust port 36. The other end of the casting block 29 is hollowed to form a chamber 42 (Figs. 3 and 7) that houses a valve "kick-over" 35 device hereafter described that actuates the rock shaft 39 and reversing valve 40.

Secured to the outer face of the disc 34 by screws 43 (which also secure the disc 34 to the block casting 29) is a valve chest casting 44, the form and structure of which are best shown in Fig. 8. The flat top wall 45 of this casting, in cooperation with a cover 46, forms a valve chamber 47 that is supplied with compressed air through an intake pipe 48 equipped with a manually controlled cut-off valve 49 (Fig. 1). In the wall 45 are a pair of ports 50 and 51, and a slot 52 extending between said ports. Controlling the ports 50 and 51 is a sliding master valve 53 that automatically directs the flow of compressed air alternately to the motors of the two jacks A and B. As shown in Figs. 3 and 4, the top of the valve 53 and the under side of the cover 46 have registering grooves in which lies a guide block 54 pressed downwardly by a spring 55, whereby the valve 53 is held to its seat and is movable only in a rectilinear direction. Formed in the casting 44 below the wall 45 is a cylinder 56 containing a piston 57 in which is mounted a stud 58 extending through the slot 52 and into a hole in the under side of valve 53. Compressed air entering the ends of the cylinder 56 shifts the valve 53 through the piston 57 and stud 58.

The port 50 communicates with a descending duct 59 on the outer side of cylinder 56, and this duct 59 leads into the chamber 60 (Fig. 3) of the reversing valve 40. In the under side of valve 53 is an arcuate groove 61. In the position of the valve 53 shown in Figs. 4 and 6, compressed air is flowing downward through port 50 to the motor of jack A, and at the same time the port 51 is covered by the valve so that compressed air cannot flow to the motor of jack B. In the reverse position of valve 53 the port 50 is covered and compressed air flows downward through port 51 and a duct 62 (Fig. 3) to and through a pipe 75 63, hose 64 (Fig. 1) and pipe 65, into the valve

chamber 66 (Fig. 8) of the reversing valve 40' of the motor of jack B, this valve chamber 66 being formed between disc 34' and a cover 66' and being functionally identical with valve chamber 60 of the reversing valve 40 of jack A. From this point on the air conducting and controlling devices of jack B are identical with those above described in connection with jack A, as clearly shown in Fig. 8.

Describing now the means for automatically shifting the master valve 53 through piston 57 so as to alternately actuate the two jacks, in the cover 46 is mounted a short pipe 67 in which is a valve 68 (Fig. 9) normally held to its seat by a spring 69. The pipe 67 has a cap 70 through which loosely projects the valve stem 71. Referring to Figs. 2, 5 and 10, on the top plate 11 of the motor cylinder is a forked lug 72 in which is pivoted at 73 a striker member of the form best shown in Fig. 10 and comprising an upright body 74 having an inclined cam surface 75 on its upper end, an inwardly extending arm 76 mounted on the pivot pin 73, and an outwardly extending flat striker arm 77 overlying the valve stem 71. The lower end of the cam 75 is undercut to form a narrow lip 78. Keyed to the plunger stem 18 is a collar 79 formed with spaced lugs 80 between which is mounted on a pivot pin 81 a dog 82 that is normally held in upright position with its upper end in contact with the collar 79 by a light spring 83. On the lower end of the dog is a lip 84 that, as the plunger stem descends, wipes over the cam 75, and rocks the striker to the dotted line position shown in Fig. 10, thus opening the valve 68. During the final part of this movement the lip 84 of the dog slides off the cam 75, and then the valve spring 69 instantly closes valve 68 and simultaneously rocks the striker back to the full line position shown in Fig. 10 wherein the lip 78 of cam 75 overlaps the lip 84 of dog 82. The closing of valve 68, of course, prevents the waste of compressed air while the plunger stem remains in the fully lowered position. As the plunger stem rises, the dog tilts forwardly and the lip 84 slips away from the lip 78 without rocking the striker (the valve spring being strong enough to prevent this), and the light spring 83 restores the dog to upright position.

A pipe 85 (Fig. 1) connects the valve casing 67 above valve 68 with one end of the cylinder 56 (Fig. 4) so that, the instant the valve 68 is opened the position of the master valve 53 is reversed, and the jack B is put in operation. At the end of the down stroke of the plunger of jack B the valve in casing 67' is opened and air flows through a hose 66 (Fig. 1) and pipe 67 to the other end of cylinder 56 (Fig. 4), again reversing the master valve 53. It may here be explained that the valve stem 71 has a sufficiently loose fit in the cap 70 so that, after valve 68 has re-seated itself, the compressed air in cylinder 56, after it has shifted piston 57, can slowly escape around the valve stem while the companion jack is being operated.

The purpose of the groove 61 in the underside of the master valve 53 is to vent the valve chamber 66 at the end of the down stroke of jack B, at which time the valve 53 is shifted to the position shown in Figs. 4 and 6. Compressed air trapped in chamber 66 when reversing valve 40' closes port 35' flows back through hose 64, pipe 63, duct 62, port 51, groove 61, and slot 52 into and through a duct 88 (Fig. 4) in the wall 45, and thence to atmosphere through a vent pipe 89 (Fig. 8). This

vent feature, although preferably used, is not indispensable, as the mechanism is operative without it.

It remains to describe the automatic mechanism for actuating the reversing valve 40. The valve "kick-over" device, before referred to, is a quick-action spring valve-reversing device best shown in Figs. 7 and 8, and in its preferred form comprises the following parts. Keyed on the rock shaft 39 is a yoke in the form of a collar 90 formed with upper and lower projecting arms 91 and 92. Also loosely mounted on rock shaft 39 and straddling the yoke are a pair of like parallel arms 93 connected at one end by a pivot pin 94 and at their other end notched to form a pair of spaced fingers 95. The two arms 93 are also rigidly connected just inwardly of the pivot 94 by a cross piece 96 that lies between the arms 91 and 92 of the yoke. The twin arms 93 form one limb of a toggle, the other limb of which consists of a rod 97 pivoted at one end on the pin 94 and at its other end mounted in a shaft 98 that is mounted in the side walls of the chamber 42. A thrust spring 99 encircles the rod 97 being confined between the pivoted end of the yoke and the shaft 98. For actuating this valve-reversing device in both directions, a vertical rod 100 is slidably mounted in the top wall of the chamber 42 and in the top plate 11 of the motor cylinder, its upper end projecting somewhat above the plate 11. Secured in the collar 79 is a depending rod 101 having on its lower end a foot 102 (Fig. 2); and adjustably keyed to the rod 100 is an arm 103 apertured for the passage of the rod 101. A laterally projecting portion of the collar 79 (Fig. 5) not only supports the depending rod 101, but also has adjustably mounted therein a screw 104 located directly above the kick-over actuating rod 100 so that it strikes and depresses the latter each time the plunger stem 18 approaches the lower limit of its travel. In the lower portion of the rod 100 lying within the chamber 42 is a cross pin 105, the two projecting ends of which extend between the fingers 95 of the arms 93, as clearly shown in Fig. 8. The position of the arm 103 on the kick-over actuating rod 100 determines the length of stroke of the plunger. If a relatively long stroke is desired, the arm 103 is set well up on the rod 100. If a relatively short stroke is desired, the arm is set lower down.

In operation, when the plunger has risen to such a point that the foot 102 strikes the arm 103, the rod 100 is raised, and the kick-over toggle is expanded and the instant its pivot 94 passes the dead center position, the spring 96 instantly re-acts causing the cross piece 96 to strike the arm 92, and thus rock the shaft 39 by a quick movement, thus actuating the reversing valve 40, which, as above described, shuts off the passage of air beneath the plunger and opens the cylinder to exhaust, so that the plunger begins its descent, the speed of the descent being regulated by the exhaust throttle valve 33. Just before the plunger reaches the limit of its downward movement, the rod 100 is struck and moved downwardly by the striker pin or screw 104, and this actuates the kick-over mechanism in the reverse direction, back to the position shown in Fig. 7, thus by a quick movement again shifting the reversing valve 40 back to its former position to cut out the exhaust and start another cycle of plunger movement. However, as previously described, at the completion of a cycle movement of one plunger, the master valve 53 is shifted by the opening of the valve 68 by the striker arm 11 so that each of the

jacks does not resume operation until the completion of the cycle of movement of its companion jack. The foregoing describes a complete cycle of operation of one jack. Shifting of the master valve 53 at the completion of the operation of one jack directs the compressed air through pipe 63 and hose 64 into the valve chamber of the other jack, causing a complete cycle movement of said other jack while the first jack is at rest; said other jack being equipped with the same valve mechanism and quick action operating means controlling the supply and exhaust of the compressed air as the first jack.

If only one jack is required for use, the jack B alone may be employed by simply disconnecting hose 64 from pipe 63 and connecting it to a source of compressed air and, preferably, plugging the valve 67' to avoid waste of the air that would otherwise be used to actuate the reversing valve 53. It will be observed from Fig. 8 that in the jack B the valve 67' is mounted directly on the unit 34', and is provided with a port 106 in the face of the unit 34' communicating constantly with the reversing valve chamber 66; the advantage of this construction being that, if a customer does not wish a twin jack machine, he can be furnished a single jack machine such as the jack B, with the unit 34' and its valve 67' omitted, and the grooves 37' and 38' of unit 34' transferred to the face of the unit 29'.

Manifestly, detail changes may be made in the structural features of the parts described without changing its essential character or departing from the principle of the invention; and hence I do not limit the latter to the structural details herein presented for purposes of illustration, but reserve such variations, modifications and mechanical equivalents as fall within the spirit and purview of the claims.

I claim—

1. In a vehicle tilting machine of the class described, the combination with two jacks each including a fluid pressure motor and a reciprocable member actuated upwardly by said motor, of a master valve operative to direct the pressure fluid alternately to the two motors, means actuated by each reciprocable member during its rising movement for opening its motor to exhaust, and means actuated by each reciprocable member at the final part of its downward movement for actuating said master valve in a direction to direct the pressure fluid to the other motor.

2. In a vehicle tilting machine of the class described, the combination with two jacks each including a cylinder and a reciprocable plunger and plunger stem actuated upwardly by fluid pressure beneath said plunger, of a master valve operative to direct the pressure fluid alternately to the two cylinders, means actuated by each plunger stem during its rising movement for opening its cylinder to exhaust, and means actuated by each plunger stem at the final part of its downward movement for actuating said master valve in a direction to direct the pressure fluid to the other cylinder.

3. In a vehicle tilting machine of the class described, the combination of two jacks each including a fluid pressure motor having a reversing valve controlling the flow of pressure fluid into and its exhaust from said motor and a reciprocable member actuated upwardly by said motor, a master valve operative to direct the pressure fluid alternately to the two motors, means actuated by each reciprocable member during its rising movement for shifting its re-

75 70 65 70 75

versing valve from supply to exhaust position and during its downward movement for shifting its reversing valve from exhaust to supply position, and means actuated by each reciprocable member at the final part of its downward movement for actuating said master valve in a direction to direct the pressure fluid to the other motor.

4. In a vehicle tilting machine of the class described, the combination of two jacks each including a cylinder, a reciprocable plunger and plunger stem actuated upwardly by fluid pressure beneath said plunger, and a reversing valve controlling the flow of pressure fluid into and its exhaust from said cylinder, a master valve operative to direct the pressure fluid alternately to the two cylinders, means actuated by said plunger stem during its rising movement for shifting its reversing valve from supply to exhaust position and during its downward movement for shifting its reversing valve from exhaust to supply position, and means actuated by each plunger stem at the final part of its downward movement for actuating said master valve in a direction to direct the pressure fluid to the other motor.

5. In a vehicle tilting machine of the class described, the combination with two jacks each including a fluid pressure motor and a reciprocable member actuated upwardly by said motor, of a master valve operative to direct the pressure fluid alternately to the two motors, a fluid pressure motor for actuating said master valve, means actuated by each reciprocable member during its rising movement for opening its motor to exhaust, and means actuated by each reciprocable member at the final part of its downward movement for admitting pressure fluid to the motor of said master valve, whereby to shift said master valve to a position where it admits pressure fluid to the other motor.

6. In a vehicle tilting machine of the class described, the combination with two jacks each including a cylinder and a reciprocable plunger and plunger stem actuated upwardly by fluid pressure beneath said plunger, of a master valve operative to direct the pressure fluid alternately to the two cylinders, a fluid pressure motor for actuating said master valve, means actuated by each plunger stem during its rising movement for opening its cylinder to exhaust, and means actuated by each plunger stem at the final part of its downward movement for admitting pressure fluid to the motor of said master valve, whereby to shift said master valve to a position wherein it admits pressure fluid to the other cylinder.

7. In a vehicle tilting machine of the class described, the combination of two jacks each including a fluid pressure motor having a reversing valve controlling the flow of pressure fluid into and its exhaust from said motor and a reciprocable member actuated upwardly by said motor, a master valve operative to direct the pressure fluid alternately to the two motors, a fluid pressure motor for actuating said master valve, adjustable means actuated by each reciprocable member during its rising movement for shifting its reversing valve from supply to exhaust position, adjustable means actuated by each reciprocable member during its downward movement for shifting its reversing valve from exhaust to supply position, and means actuated by each reciprocable member at the final part of its downward movement for admitting pressure

fluid to the motor of said master valve, whereby to shift said master valve to a position wherein it admits pressure fluid to the other motor.

8. In a vehicle tilting machine of the class described, the combination of two jacks each including a cylinder, a reciprocable plunger and plunger stem actuated upwardly by fluid pressure beneath said plunger, and a reversing valve controlling the flow of pressure fluid into and its exhaust from said cylinder, a master valve operative to direct the pressure fluid alternately to the two cylinders, a fluid pressure motor for actuating said master valve, a collar fast on each plunger stem, means, including an element carried by said collar, for shifting said reversing valve from supply to exhaust position during the rising movement of said plunger stem, other means, including an element carried by said collar, for shifting said reversing valve from exhaust to supply position during the downward movement of said plunger stem, and other means, including an element carried by said collar and operating during the final part of the downward movement of said plunger stem, for admitting pressure fluid to the motor of said master valve, whereby to shift said master valve to a position wherein it admits pressure fluid to the other cylinder.

9. In a vehicle tilting machine of the class described, the combination with two jacks each including a fluid pressure motor and a reciprocable member actuated upwardly by said motor, of a master valve operative to direct the pressure fluid alternately to the two motors, a fluid pressure motor for actuating said master valve, flow ducts for compressed air leading to opposite ends respectively of said last named motor, self-closing valves in said flow ducts, means actuated by each reciprocable member during its rising movement for opening its motor to exhaust, and means actuated by each reciprocable member at the final part of its downward movement for opening the self-closing valve associated therewith.

10. In a vehicle tilting machine of the class described, the combination with two jacks each including a cylinder and a reciprocable plunger and plunger stem actuated upwardly by fluid pressure beneath said plunger, of a master valve operative to direct the pressure fluid alternately to the two cylinders, a fluid pressure motor for actuating said master valve, flow ducts for compressed air leading to opposite ends respectively of said last named motor, self-closing valves in said flow ducts, a collar fast on each plunger, means, including an element carried by said collar, for opening the associated cylinder to exhaust during the rising movement of the plunger, and means, including an element carried by said collar, for opening the associated self-closing valve at the final part of the downward movement of the plunger.

11. In a fluid pressure lifting jack, the combination with a motor cylinder, plunger and plunger stem, of valve mechanism controlling the supply and exhaust of pressure fluid to and from said cylinder including a valve chamber, means for conducting pressure fluid to said chamber, ducts leading from said chamber to said cylinder and to exhaust respectively, a rock-shaft, a reversing valve fast on one end of said rock-shaft in said chamber controlling said ducts, a quick-action spring valve-reversing device operatively associated with said rock-shaft, and means actuated by said plunger stem for trip-

ping said valve-reversing device into action at the upper and lower limits of travel of said plunger stem.

12. In a fluid pressure lifting jack, the combination with a motor cylinder, plunger and plunger stem, of valve mechanism controlling the supply and exhaust of pressure fluid to and from said cylinder including a valve chamber, means for conducting pressure fluid to said chamber, ducts leading from said chamber to said cylinder and to exhaust respectively, a rock-shaft, a reversing valve fast on one end of said rock-shaft in said chamber, a quick-action spring valve-reversing device operatively associated with said rock-shaft, a reciprocable rod having a cross-pin for actuating said valve-reversing device, and means carried by said plunger stem for raising and lowering said rod at the upper and lower limits of travel respectively of said plunger stem.

13. In a fluid pressure lifting jack, the combination with a motor cylinder, plunger and plunger stem, of valve mechanism controlling the supply and exhaust of pressure fluid to and from said cylinder including a valve chamber, means for conducting pressure fluid to said chamber, ducts leading from said chamber to said cylinder and to exhaust respectively, a rock-shaft, a reversing valve fast on one end of said rock-shaft in said chamber, a quick-action spring valve-reversing device operatively associated with the other end of said rock-shaft, a vertically reciprocable rod having on its lower end a cross-pin for actuating said valve reversing device, a collar keyed to said plunger stem, and adjustable means, including elements carried by said collar, for raising and lowering said rod at the upper and lower limits of travel respectively of said plunger stem. 5 10 15

ERNST C. CLAUS.
